US0D1068656S

(12) **United States Design Patent** (10) **Patent No.:** **US D1,068,656 S**
(45) **Date of Patent:** **** Apr. 1, 2025**

(54) **CHARGER**

(71) Applicant: **Masimo Corporation**, Irvine, CA (US)

(72) Inventors: **Paolo Sandro Trevisan**, Key Biscayne, FL (US); **Francisco Barboza Grasa**, Miami, FL (US); **Isaac Drickhamer**, Miami Beach, FL (US); **Jason Wang**, Miami, FL (US); **Nicholas Evan Barker**, Laguna Beach, CA (US); **Franco Lodato**, Winter Garden, FL (US); **Chad A. DeJong**, Los Angeles, CA (US)

(73) Assignee: **Masimo Corporation**, Irvine, CA (US)

(**) Term: **15 Years**

(21) Appl. No.: **29/875,877**

(22) Filed: **May 11, 2023**

(51) LOC (15) Cl. **13-02**

(52) U.S. Cl.

USPC **D13/108**

(57) **CLAIM**

The ornamental design for a charger, as shown and described.

DESCRIPTION

FIG. 1 is a top perspective view of a first embodiment of a charger embodying our new design;

FIG. 2 is another top perspective view thereof;

FIG. 3 is a front view thereof;

FIG. 4 is a back view thereof;

FIG. 5 is a side view thereof;

FIG. 6 is another side view thereof;

FIG. 7 is a top view thereof; and

FIG. 8 is a bottom view thereof.

FIG. 9 is a top perspective view of a second embodiment of a charger embodying our new design;

FIG. 10 is another top perspective view thereof;

FIG. 11 is a front view thereof;

FIG. 12 is a back view thereof;

FIG. 13 is a side view thereof;

FIG. 14 is another side view thereof;

FIG. 15 is a top view thereof; and,

FIG. 16 is a bottom view thereof.

Broken lines, where shown, are used to illustrate portions of the charger that form no part of the claimed design.

1 Claim, 10 Drawing Sheets
